UNITED STATES PATENT OFFICE.

JOHN REID, OF LONDON, ENGLAND.

FURNACE.

Application filed May 10, 1924. Serial No. 712,382.

To all whom it may concern:

Be it known that I, JOHN REID, a subject of the King of Great Britain and Ireland, residing at London, England, have 5 invented Improvements Relating to Furnaces, of which the following is a specification.

In the distribution of air to furnaces it frequently happens, particularly in forced 10 draft furnaces, that streams of air meet in the furnace front and obstruct the even flow of the air into the furnace, results being that the air has to be subjected to greater pressure than is really necessary and that 15 surges and eddies are set up and the flame unevenly supplied with air which however reaches it at high velocity; under these conditions efficient and economical combustion cannot be attained.

20 The object of the present invention is to overcome these disadvantages, more especially in forced or mechanical draft furnaces burning liquid fuel.

According to the invention, the air is 25 admitted to a circular air pocket in the furnace front and is gradually diverted by an irregular or ceratoid cusp shaped plate so as to flow in the desired direction, for instance in the case of an oil burning furnace, spirally around the interior of a cylinder, part of the wall of which is cut away to admit the stream of air. This cylinder is mounted in the front opposite the opening into the furnace and the burner tube 30 rounded, it may be, by a perforated or slotted air distributing sleeve, extends through it. Some of the air may also flow around the exterior of the cylinder which itself may be perforated or slotted. The ceratoid cusp 35 shaped plate may be adjustable within the furnace front, and may be secured to the flare or the ashpit door.

In the accompanying drawings the invention is illustrated as embodied in a sectional front for a furnace convertible for burning either coal or oil, the front being shown fitted for burning oil, but it is to be understood that the invention may be embodied in other forms of furnace fronts.

50 Fig. 1 is a vertical longitudinal section through the front and Fig. 2 a front elevation partly in section.

a and *b* are the front and back plates of the front each being formed with projecting 55 portions which meet and form the flare *c* and the fuel casing or firebox *d*, the bottom

of which is closed by a removable sill when coal is being burned; *e* is an air casing with regulating air valve *f* and *g*, *g* are valves admitting air to the lower part of the air 60 pocket within the front. This construction is well known.

To the flare *c* a ceratoid cusp shaped plate *h* is removably secured in a position to the right of the centre line of the front so that 65 air entering by the left hand valve *g* will be gradually diverted upwardly into the fuel casing or firebox *d* which is fitted with a removable air guide or cylinder *i* the lower part of which is cut away as shown. The 70 oil burner tube *k* extends through the air guide or cylinder *i* and the air flows spirally around it and through the opening *l* in the fire brick partition *m* which closes the mouth of the furnace. The plate *h* may be extended to the partition *m*.

Usually only the left hand valve *g* will be open but if the right hand valve *g* is also open the air admitted therethrough will also be diverted in a similar, though less gradual 80 manner by the other side of the cusp shaped plate *h*, the two streams thus being blended smoothly into a stream which enters and flows spirally around the interior of the cylinder *i*.

In the case of a multiple furnace steam boiler, the wing furnaces may be fitted with ceratoid cusp shaped plates set respectively to the left hand (as shown) and right hand of the centre line of the front.

90 What I claim is:—

1. In a furnace front having a circular air pocket therein, a ceratoid cusp shaped device adapted to gradually divert air admitted thereto from either side of said device so that it flows in the desired direction to said pocket, substantially as described.

2. In a furnace front, the combination of a ceratoid cusp shaped plate adapted to gradually divert air admitted thereto of a 100 partial cylinder into which the stream of air is diverted and around the interior of which it flows spirally to the opening into the furnace, substantially as described.

3. The combination with a furnace front having laterally disposed air inlet openings and a rear outlet to the furnace, a ceratoid cusp-shaped plate located within the front so as to present concave surfaces to the flow of air and gradually divert the air towards 110 the outlet from the front to the furnace.

4. In combination with a furnace front

having laterally disposed air inlet openings, a ceratoid cusp-shaped plate located within the front so as to present concave surfaces to the flow of air and gradually divert opposing streams of air until they blend in a common stream.

5. In combination with a furnace front having laterally disposed air inlet openings, a ceratoid cusp-shaped plate located within the front so as to present concave surfaces to the flow of air on opposite sides of said front and gradually divert the air in opposing streams until blended in a common stream; said concave surfaces being unequal.

6. In combination with a furnace front 15 having laterally disposed air inlet openings, a ceratoid cusp-shaped plate located within the front so as to present concave surfaces to the flow of air on opposite sides of said front and gradually divert the air in opposing streams until blended in a common stream; each of said concave surfaces being in the form of the segment of a circle and one of the circles described by the segments being of larger diameter than the other. 20 25

Signed at New York city, N. Y., U. S. A., this 9th day of May, 1924.

JOHN REID.
